UNITED STATES PATENT OFFICE.

ERNST FLACH, OF PHILADELPHIA, PENNSYLVANIA, ASSIGNOR TO LARGMAN-GRAY COMPANY, OF PHILADELPHIA, PENNSYLVANIA.

METHOD OF KNITTING FULL-FASHIONED HOSIERY.

Application filed March 5, 1926. Serial No. 92,501.

This invention relates to new and useful improvements in a method of knitting full fashioned hosiery, more particularly to the knitting of the welt to the leg portion in ladies' hosiery, the primary object of the invention being to provide in such method a lock stitch between the welt and the leg portion which will prevent garter "runs" from entering the leg portion of the stocking.

10 A further object of the invention resides in the formation of a lock stitch between the welt and leg portion of the stocking in a new manner which does not require the addition of any new elements to the knitting machine and which stitch, when formed, will not produce any visible obstruction or projection in the knitted fabric.

A further object resides in providing a method of producing a lock stitch between the welt and the leg portion of a stocking by folding over the welt, when the latter is completed, so that one end of the latter rests on top of the knocking-over bits and the other end rests on top of the nose of the sinkers.

25 With these and other objects in view, my invention consists in the simple method hereinafter and more particularly described.

In the accompanying drawing, forming a part of this application,

30 Figure 1 is a side elevation, partly in section, illustrating in diagrammatic manner the positions of the sinkers, knocking-over bits, knitting needle and a welt of a stocking being knitted, with relation to one another,

35 Figure 2 is a similar view illustrating the manner in which the welt is folded over to permit one end to rest upon the knocking-over bits and the other end to rest upon the sinkers, whereby the lock stitch may be formed,

40 Figure 3 is a diagrammatic view illustrating the relation of the end threads of the welt with respect to the needle, in the formation of a lock stitch,

45 Figure 4 is a similar view showing the relation of the aforesaid threads when the lock stitch is completed, and

50 Figure 5 is a fragmentary elevation of a stocking showing the welt and the lock stitch connecting same with the upper leg portion.

I am aware of the fact that various forms

of stitches and means have been provided and used to prevent garter "runs" from projecting below the lower edge of the welt of a stocking. Usually in these methods of manufacture, the stitch becomes visible between the welt and the leg portion of the stocking and in many instances it is so accentuated as to provide a projection on the stocking which, to the trade, is found objectionable for various reasons. Moreover, in these various methods of producing a stop for "runs", considerable time is lost in the knitting of the hosiery and in many instances added elements are necessarily applied to the machine to carry on the work, which is added expense in the manufacture of the goods. My invention contemplates a method which requires no additional elements to the machine and no added work on the part of the operator of such machine. Furthermore, my improved method produces a stitch, or what may be termed a "run stop" which is invisible.

55 In describing my invention, I shall refer to the drawing in which similar reference characters designate corresponding parts throughout the several views and in which 1 designates a knocking-over bit of the usual character above which is positioned a sinker 2, mounted and arranged in a conventional manner. The numeral 3 designates a knitting needle having the usual beard 4, said needle being mounted in the bar 5 which is supported in the customary manner.

60 The numeral 7 designates the completed welt which has been knitted, the same being held, as shown in Figure 1, in substantially horizontal position by the hooks carried on the transfer bar 6, the latter being supported in the usual or any preferred manner. For convenience, I have designated the ends of this welt 7 by the numerals A and B and the Figure 1 is intended to illustrate the welt when it has been completely knitted, ready 65 to be turned or folded over.

65 Under the ordinary method of knitting full-fashion hosiery, the welt is knitted to a point as shown in Figure 1, whereupon the outer end B of the welt is transferred to the knitting needles 3 so that both ends A and B rest upon the knocking-over bits and the leg portion of the stocking is then knitted in the usual manner. In this method a stitch is

formed between the welt and the leg portion through which a garter "run" may extend into the leg portion. In my improved method, the welt is knitted to its full length as usual and after the completion of this length of knitting, the needle bar is brought forward in the ordinary manner and the end B of the welt transferred over the needles 3, also in the usual manner, but this end B of the 10 welt is placed and allowed to rest upon the sinkers 2. In accomplishing this end the end B is kept above the sinkers and the needle bars are then put back in place, whereupon the fabric is pressed down to rest on the top 15 of the nose of the sinkers. Thus, the end A of the welt rests on top of the knocking-over bits and the end B rests upon the nose of the sinkers. This position of the ends of the welt, when the latter is transferred to the 20 needles 3, is clearly shown in Figure 2 of the drawing. By this method, the stitch of the welt which is resting on top of the sinkers enters the next stitch in the course which is run across the work, both stitches being 25 placed in the beard of the needle so that when said needle operates downwardly said beard closes and the stitch at the end of the welt and the next stitch of the stocking are pulled through the stitch at the end A of the welt 30 to produce a distinct and absolute lock stitch. The relation of the threads to the needle prior and subsequent to the formation of this lock stitch is clearly illustrated in Figures 3 and 4, respectively, of the drawing.

35 As a result of the operation and method above described, a lock stitch is formed and the machines are continued in operation to complete the knitting of the leg portion of the stocking. The formation of this lock stitch 40 does not cause any apparent protrusion in the stitches and, in fact, provides an invisible "run stop" between the welt and the leg portion. Inasmuch as "runs" or "ladders" are formed usually as a result of the strain and 45 pull applied to the welt by the garter clips the usefulness of a lock stitch between the welt and the leg portion to prevent such "runs" entering the leg portion will doubtless be apparent, and it is obvious as to the advantages of a stitch of the character above mentioned which will accomplish the desired result and remain invisible.

50 From the foregoing description, it is thought the method of operation in carrying out my invention will be thoroughly understood and it will be seen that I have provided a simple, inexpensive and efficient means for

accomplishing a result extremely desirable in this art.

Having thus described my invention, what I claim is:

1. A method of knitting full fashioned hosiery consisting in knitting the welt portion, transferring only the first course thereof to the knitting needles to rest on the sinkers 65 and continuing the knitting operation.

2. A method of knitting full fashioned hosiery consisting in knitting the welt portion, moving the needle bar forward, transferring only the first course of the welt to 70 the knitting needles to rest upon the sinkers and continuing the knitting operation.

3. A method of knitting full fashioned hosiery consisting in knitting the welt portion, moving the needle bar forward, transferring only the first course of the welt portion to the knitting needles above the sinkers, moving the needle bars rearward pressing said first course of the welt portion downwardly to rest on the nose of the sinkers, and 80 continuing the knitting operation.

4. In the knitting of full fashioned hosiery, a method of producing a lock stitch between the welt and leg portions consisting in knitting the welt, transferring only the first course thereof to the knitting needles above the sinkers, pressing said first course of the welt downwardly to rest on the nose of the sinkers and continuing the knitting operation.

5. The method of knitting the welt and leg of a stocking on a flat bar knitting machine with a lock stitch consisting in knitting the complete welt and leaving the loops of the final course upon the needles, then shifting 95 the needles to clearance position with relation to the sinkers that the final course with loops may fall along the needles, then transferring the loops only of the initial course of the welt to the upper portions of the needles, then 100 moving the needles back to knitting position whereby the final course of welt loops rest upon the upper edges of the knocking over bits and the loops only of the initial course rest upon the upper edges of the sinkers, then 105 feeding the yarn to the needles and finally depressing the needles whereby the yarn and the only loops of the initial course of the welt are carried through the loops of the final course of loops of the welt providing substantially a lock stitch and forming the loops of the initial course of the leg of the stocking.

In testimony whereof I affix my signature.
ERNST FLACH.
